C. AHLTEEN,
SANITATION APPLIANCE,
FILED MAR. 15, 1920.

UNITED STATES PATENT OFFICE.

CARL AHLTEEN, OF LEAVENWORTH, KANSAS.

SANITATION APPLIANCE.

Application filed March 15, 1920. Serial No. 366,035.

To all whom it may concern:

Be it known that I, CARL AHLTEEN, a subject of the King of Sweden, residing in the city of Leavenworth, in the county of 5 Leavenworth and State of Kansas, have invented certain new and useful Improvements in Sanitation Appliances, of which the following is a specification.

My invention relates to vapor bath appliances and has particular reference to their use in connection with steam and heated air. The object of this invention is to provide a combination bed or hammock support and steamer, which is adjustable to 15 different sizes of persons and adapted for either homes or hospitals whether equipped with steam plants or not. Another object of this invention is to provide a simple, economical and readily assembled structure 20 that may be readily assembled or taken apart, which shall occupy a minimum of space and which includes in the supporting framework the necessary conduits for plain or medicated vapors by utilizing tubular 25 frame members, or piping and fittings therefor, that are staple articles of commerce and readily procured.

With the above named general objects in view my invention consists in the novel construction, combination and arrangement of parts, all as hereinafter described in detail, illustrated in the accompanying drawings and more particularly pointed out in the appended claims.

35 In the drawings:—

Figure 1 is a perspective view of a structure embodying my invention with the inlet valve shown in section.

Figure 2 is a face view of the valve shown 40 in section in Figure 1.

Figure 3 is a section of the valve taken in a vertical plane at right angles to the vertical plane of Figure 2.

In the several views 2 represents the 45 main steam distributing pipe which is also caused to serve as a portion of the bed or hammock supporting frame rails including top rails 3 and 4 which are also shown as tubular members but of smaller cross section than the pipe 2, and which substantially parallel the latter. The upper rails 3 and 4 are supported on a series of substantially V-shaped bearing brackets, each of which provides a pair of legs or arms 5 and 55 6 which meet in a connective portion 7 that is convexed in conformity with the curva-

ture of the upper side of the conduit 2 and is secured thereto by means of bolts 8 the heads of which 9 engage the connective portion 7 while the bolt-nuts 10 engage the 60 under-side of the member 2. Each of the arms 5 and 6 is bifurcated at its upper end, or provided with a recess in the form of a pair of fixed jaws 11, in which the rails 3 and 4 are removably held, as shown. 65

From the rails 3 and 4 is suspended by means of buckle straps 13 and 14, or other convenient means, a hammock or bed bottom 15 to the edges of which the straps 13 and 14 are secured. This hammock or bed 70 bottom 15 may be made of any flexible material adapted to comfortably support a person in a reclining position and being sufficiently porous, open or perforated to permit steam or vapor to pass through said 75 material.

The rails 3 and 4 together with the hammock 15 thus form substantially an independent structure adapted to be used as a stretcher or carrying portion on which a 80 sick person may be carried and such person's bed mounted for vapor treatment.

In the upper portion of the pipe 2 are rows of perforations, preferably a central and uppermost row 16 and a row 17 at each 85 side of said row 16, through which vapor from the interior of the conduit 2 is directed upwardly against the hammock 15 and the occupant thereof.

In the present embodiment of my invention the pipe 2 is shown as consisting of a series of sections or short pipe lengths 18, 19, 20 and 21 connected by T-fittings 22, 23 and 24. The fitting 23 includes a valve portion, the rotary core of which is designated 90 by the numeral 25. This valve may be a standard brass gate valve, or any two-way valve, and is, as shown, placed in the middle portion of the conduit 2, where it is designed to divide said conduit into an upper and a 100 lower body portion and confine the flow to either portion, or divide it equally as well as regulating the quantity and force of steam conduction towards either or both ends of the conduit 2. The details of the particular 105 form of valve employed for the purpose of illustrating my invention are shown in Figures 2 and 3, and may be varied in any desired manner to effect the stated control without departing from the spirit of this invention. In Figure 1 the relation of the 110 ports of this valve to the conduit 2 is shown,

and as consisting of a bore through the portion 25 the ends of which are designated as inlet or outlet ports 26 and 27, and a bore at right angles to the bore 26, 27 and in 5 communication therewith, which is labeled 28. In Figure 1 the position of the valve 25 admits steam to both ends of the conduit 2, while a quarter revolution from the Fig. 1 position, which is shown in Figure 3, shuts 10 off one end and admits a full volume flow into the opposite end. 29 designates the opening from the valve into the pipe section 20 with which the port 27 is in register while the port 26 registers with the corresponding 15 opening into the section 19. If the port 28 is rotated into the place of the port 27 steam will enter the conduit 2 only to the right (Figure 1) of the valve, whereas if rotated into the place of the port 26 steam will be 20 admitted only to the left hand end of said conduit and with a volume corresponding to the degree of opening in either instance.

The valve-fitting 23 has its vertical branch connected with a hollow post, or pipe section 25 30, mounted in or secured to a base 31 on which is lugs or ears 32 having screw or bolt holes 33 therein for screws or bolts by means of which the base may be secured to a floor or platform. The pipe 30 is the trunk member 30 of the frame as a support and the trunk feed pipe for the conduit 2, and is conveniently assisted in supporting the pipe 2 by a pair of radius brace rods or pipes 34 and 35 shown coupled by ordinary and well known 35 unions to the fittings 22 and 24. In the base 31 the braces 34 and 35 are likewise fastened by the ordinary and well known means, the details of which do not specifically form any part of this invention. The free ends of the 40 pipe sections 18 and 21, or the ends of the pipe 2 as a whole, are closed by the usual threaded caps or pipe end closers 36 and 37. Through a broken away opening in the base 31 the lower end of the hollow post and 45 conduit 30 is shown provided with threads 38 on which is a threaded sleeve or coupling collar 39 by means of which a steam pipe projecting up through a floor (not shown) may be connected. The member 39 may also 50 represent a closer cap similar to either 36 or 37, when, as will hereinafter appear, my improvement is to be used where no steam plant is installed, or when steam is taken into the side of the pipe 30 through a hose 55 nipple or connection 40 which is, when not in use, closed by a cap 41 which may also represent a coupling member like the member 39.

The hammock or bed bottom supporting 60 frame rails 3 and 4 are at their head-ends telescoped by legs 42 and 43 of a U-shaped and upwardly curved head member 44 to which the head-end —45— of the sheet or bed bottom 15 is attached and from which 65 said head end is suspended in a more ele-

vated position than the side edges of the bed bottom 15 and in like manner. The rails 3 and 4 serve as supports for a top blanket or covering (not shown) over the bed or hammock preferably of sufficient width to drop 70 over the sides of the frame and extend to the floor —49— if desired to form, as it were, a housing within which the vapor is detained.

Referring to the specific details of the 75 valve 25 a section of which is shown in Figure 1 in one vertical plane and of which a section is shown in Figure 3 in a vertical plane at right angles to the section plane of Figure 1. The ports 26, 27, and 28 are in 80 a revoluble or core portion —25— with a stem 71 thereon having a reduced portion 70 on which a handle or hand-wheel 72 is secured against rotary movement and held against longitudinal movement on the portion 70 by a nut 73 engaged with threads on the end of said reduced portion 70. On the opposite end of the rotary member 25, which is slightly reduced, as shown in Figure 3, toward the end opposite to that from 90 which the stem 71 projects, is a threaded stem 76 which is not shown in section like the stem 71, and which carries a nut 77 that bears against a washer 75 which overlaps, as shown in Figure 3, the edges of the opening through the fitting 23, serving as a valve casing, for the rotary part 25. The washer 75 thus prevents movement of the rotary member 25 to the left (Fig. 3) while its taper enlargement in the same direction prevents longitudinal movement of the rotary member to the right. However, as stated, the particular form of valve is immaterial so long as whatever form of valve is employed performs the stated functions. On 100 the threaded stem 76 is a nut 77 which supports the disk or washer 75 on said stem. In Figure 3 the valve is turned a quarter turn from the position in which it is shown in Figure 1 thus closing the conduit 30 to 110 the sections 20 and 21 of the distributing pipe 2.

The legs 42 and 43 are shown provided with perforations or holes 78 adapted to be engaged by stop pins 79 to hold the head extension member 44 in its partly drawn out position to lengthen the bed or hammock beyond the extension shown where necessary.

In the employment of the above-described 120 invention a temperature test is first had by covering the hammock 15 with, say, a woolen blanket and placing between the hammock and blanket a thermometer, then turning on the steam until the required temperature is reached. If too great the supply 125 of steam is lessened by means of the valves and dampers described. The bather then enters or is placed in the hammock after a thin towel or sheet is placed thereon. Af- 130

ter the bather is in the hammock he places or has placed over him supported on the arches 46 a sheet large enough to reach to the floor on both sides, thereby making an

5 enclosure detaining the steam around the body of the bather. On top of said top sheet is preferably placed a blanket of the same size as the sheet and reaching to the floor.

10 When the entire body, including the head, is to be immersed in the vapor, a towel dipped in cold water and wrung to remove excess of water. This towel is placed on the forehead with such additional cold 15 towels as may be necessary. At the conclusion of the bath the top blanket is removed and the sheet under the bather is wrapped about the body and fastened to the neck to absorb perspiration. Thereafter massaging 20 may be advantageously resorted to. After excess perspiration has been absorbed in the original sheet another sheet dipped in cold water at a temperature of from 50 to 68 should be substituted as a stimulant, ac-

cording to the person's strength, to skin re- 25 action, which may be followed by a cold plunge if desired.

I claim as my invention—

1. In a steam bath apparatus, the combination with supporting rails, of V-shaped 30 arms on which said rails are mounted, a perforated steam conduit on which said arms are mounted, and a hammock suspended from and between said rails.

2. In a steam-bath apparatus, the combination with a central supporting stand which includes a vertical inlet-pipe, of a horizontal distributing pipe supported by and communicating with said inlet pipe, upwardly projecting radial arms removably 40 mounted on said distributing pipe, parallel rails mounted on said arms, and a hammock suspended from said rails over said distributing pipe.

In testimony whereof I have hereunto 45 signed my name.

CARL AHLTEEN.
